UNITED STATES PATENT OFFICE.

SABINA PENROD, OF YUCAHILL, NEBRASKA.

CROCHET-RING.

4,191,457.

Specification of Letters Patent. Patented July 18, 1916.

Application filed February 16, 1915. Serial No. 8,590.

To all whom it may concern:

Be it known that I, SABINA PENROD, citizen of the United States, residing at Yucahill, in the county of Custer and State of Nebraska, have invented certain new and useful Improvements in Crochet-Rings, of which the following is a specification.

This invention relates to finger rings or bands, and more particularly to a ring of a peculiar form, having improvements carried thereby for guidance of the thread, yarn, or the like material, commonly used in crocheting, knitting, etc.

The primary object of my invention is to provide a ring of the above-described character which will be simple in construction, cheap to manufacture, and possess numerous advantages which facilitate its use.

Another object of my invention is to provide a ring of the above-described character which is readily receivable on a finger of the user's hand, and means is provided on the ring to guide a thread or the like in use.

A still further object of my invention is to provide guides on the ring which are so formed as to facilitate insertion thereinto and movement therethrough of a thread or the like.

With the above and other objects in view my invention resides preferably in the construction, combination, and arrangement of parts as hereinafter set forth in the specification and illustrated in the accompanying drawings, in which—

Figure 1 is a perspective view illustrating my invention as a whole and showing its application in use. Fig. 2 is a transverse sectional view of the ring. Fig. 3 is a longitudinal sectional view of my improved ring, and Fig. 4 is a front elevation of the same. Similar reference characters indicate similar parts throughout the various views of the drawings.

Referring more particularly to the drawings in which the preferred embodiment of my invention is illustrated, I provide a ring 1 of any suitable material, the said ring being substantially arcuate in cross section, as indicated at 2 to provide a substantial annular curved structure, this structure affording means to assist in the guidance of threads or the like, as hereinafter set forth in detail, and also facilitating the insertion of a finger of the user's hand, as illustrated to advantage in Fig. 1. The degree of curvature of the arcuate ring 1 may be

changed at will in the manufacture of the device, I desiring to lay stress on the fact that the curving of the ring in the manner shown is one of its most advantageous features.

I provide a plurality of guides which are disposed in spaced-apart relation substantially intermediate the marginal edges 3 and 4 of the ring, the said guides being looped and comprising a plurality of hook members 5 and 6, integrally formed or otherwise carried by the ring 1, the outer free extremities of the said hook members 5 and 6 overlapping in spaced relation as indicated at 7 in Fig. 3, whereby a thread, twine or the like may be readily inserted into the loops formed by the hook members 5 and 6, and from which dislodgment of the twine under normal conditions is prohibited. One or the other of the hook members 5 and 6 may be slightly resilient in nature so that they may be separated slightly upon insertion of the thread therebetween, and will return to their normal positions after the thread has passed into the loop. The position of the thread is shown to advantage in Fig. 1, the user's hand being designated 8 and the index finger thereof 9, on which the ring 1 is received, and the yarn, thread or the like is designated 10. It will be noted in this view that the thread 10 passes through two of the loop members mentioned, these loop members being substantially alike in formation, a description of one of them being hereinbefore set forth in detail. The number of these loop members may be readily changed to suit the conditions, but I have found that a pair of them operate to distinct advantage and therefore have shown but a pair. For the sake of simplicity in describing my device, the loops formed by the hook members 5 and 6 have been shown designated by the numeral 11 in Fig. 1.

The use of my improvement, its advantages and construction should be gathered from the above description, and while the device has been shown as applied to the index finger, its advantages in this position do not necessarily forbid its use on other fingers of either hand of the user, but it has been found that under a great many conditions this position is very advantageous, as the free end of the thread 10 shown in Fig. 1, and designated 12 may be engaged by the other fingers of the hand so as to insure proper tensioning of the thread in use or the

- portions 10 and 12 of the thread may be intersected and looped over the ring so that friction between the portions 10 and 12 may insure proper tensioning of the thread.
- 5 A distinct advantage of my invention resides in the fact that when in position its use prevents the thread 10 or the like from making any mark or marks upon the fingers of the user, the device not alone providing a 10 guide and tensioning device but adds very much to the comfort of the user and the facility with which crocheting and other such tedious work may be accomplished.
- 15 While I have shown and described my invention as possessing a peculiar form and construction, it is desired that it be understood that I may make such changes in the details thereof that do not depart from the spirit and scope of the invention as claimed.
- 20 Having thus described my invention what I claim and desire to secure by Letters Patent, is:

Copies of this patent may be obtained for five cents each, by addressing the "Commissioner of Patents, Washington, D. C."

1. A thread guide for use on one of the fingers of the hand including a ring of substantially arcuate cross section forming a 25 channeled guide, a plurality of guiding and retaining elements thereon comprising loops formed from hook members having their extremities in overlapped spaced-apart relation for reception and movement there-through of a thread or the like.

2. A device as specified, including a ring arcuate in cross section to provide a channeled guide, a plurality of overlapping hooks on said ring forming loops to receive 30 a thread, said thread moving upon the base of said channel.

In testimony whereof I affix my signature in presence of two witnesses.

SABINA PENROD.
